GLEN L. POPE AND ABE COHEN, OF GRETNNA, NEBRASKA.

HOOK FASTENER AND REMOVABLE MOUNTING THEREFOR.

Application filed June 18, 1928. Serial No. 286,458.

This invention relates to a fastener of hook-form and a removable mounting therefor, and has for its object, broadly, to provide a metallic hook for use as a fastener, 5 the mounting of the hook being such that it may be held without being permanently attached and may be removed.

In the use of aprons by barbers, butchers, dentists and others, adjustments must be 10 made to correspond to the individual, and size of the neck or body, and it is an object of the present invention to illustrate convenient means for these adjustments.

Also since the kinds of aprons mentioned 15 require frequent laundering it is important that any metallic part used as a fastener should be removed, and the present invention has for one of its objects to provide a mounting of such construction for a metallic hook 20 that the latter may be readily attached to the apron or removed therefrom.

Another object is to provide fasteners for aprons which will not become injured during the operation of ironing or while moving 25 through a mangle in the operation of laundering, and to provide fasteners for aprons which will be durable and may be conveniently manufactured.

With the foregoing objects in view, and 30 others to be mentioned, the invention presents a new and useful construction, combination and arrangement of parts as described herein and claimed, and as illustrated in the accompanying drawing, wherein,—

35 Fig. 1 is a side view of the apron. Fig. 2 illustrates the use of the apron when folded to dispose its neck bands in register. Fig. 3 is an edgewise view of the parts shown in Fig. 2. Fig. 4 is a perspective view showing fasteners for connecting two end-portions of a neck band. Fig. 5 is a broken away view showing a flexible strip provided with a pair of eyelets for receiving a metallic hook, said strip being secured to a neck band. Fig. 40 46 6 is a sectional view on line 6—6 of Fig. 5. Fig. 7 is a view similar to that shown in Fig. 6, a metallic hook being added.

Referring now to the drawing for a more 50 particular description, the invention is shown and described in connection with an apron 8 provided at each end with a neck band 9. Each neck band preferably consists of fabric folded upon itself to provide a flexible body of ample length to surround the 55 neck with its end-portions disposed in overlapped relation.

Numeral 10 indicates a fabric strip which is provided with a plurality of eyelets 11, uniformly spaced at intervals of its length, said band being secured at its longitudinal 60 edges to the neck band by rows 12 of stitches, its ends being secured to said neck band by rows of stitches 13.

The parts thus described provide a holder or fastener for one end portion of a neck 65 band, the opposite end-portion of the neck band being provided with a metallic hook fastener which, together with its removable mounting will now be described.

For this last named fastener we provide 70 a metallic hook α consisting of a curved prong 14 having a shank 15 provided at its terminal with a projection 16. Numeral 17 indicates a flexible strip which is secured to the end-portion of the neck band opposite to the strip 10 by rows of stitches 18, stitches 19 also being used at its ends for securing said strip to the neck band. As best shown in Figs. 6 and 7 of the drawing the fabric strip 17 engages both sides of the neck band. Numerals 20 and 21 indicate a pair of eyelets 75 which are formed in the strip 17 in its inner side, its outer side being provided with a flap or finger-piece 22.

As thus described it will be seen that the 80 hook α may be readily mounted upon the strip 17 and may be removed therefrom, this being an important feature to permit laundering. It will be understood that, for mounting the hook in operative position, the 85 prong 14 may be inserted in the eyelet 21 and by pressing the hook gently the shank 15 will move through said eyelet 21, the prong 14 moving outwardly through the eyelet 20, and since the projection 16 has a greater area 90 than the eyelet 21 it will operate as a detent and prevent any further movement of the hook. Also it will be understood that the hook may be readily removed from the eyelets.

In the use of the apron, the neck band is 95 adjusted in such a manner that it will fit snugly upon the neck, especially during the operation of hair cutting by a barber when cutting the hair of a patron. It will be understood that the eyelets 11 provide for adjustments and the hook may engage in any required eyelet 11 so that the neck band may closely engage the neck. The function to be 100 discharged by the flap or hand-hold 22 is to provide a part which may be grasped when 105 adjustments are to be made. In making said 110

adjustments the flap 22 may be held by an operator while the end-portion of the band and the hook are moved for engagement of the hook in a selected eyelet 11 upon the opposite end-portion of the band, and on account of the use of the flap 22 it will not be necessary that any part of the hand or finger should be inserted between the neck band and neck of a patron, the element 22 operating as 10 a convenient holder for these purposes.

It will be appreciated that the eyelets 11 and pair of eyelets 20 and 21 will not become injured or unduly worn by operation of laundering the apron since they will not present 15 any rough surfaces such as wings or ridges.

We claim as our invention,—

1. In a removable mounting for a fastener-hook upon a flexible body, said hook including a curved prong and a shank having a 20 projection, a flexible strip disposed at the opposed sides and secured to the flexible body and provided with a flap projecting outwardly from one of the sides of said body and having a pair of eyelets for a mounting of the 25 hook at that side of the body opposite to the flap, the apertures of said eyelets being of such proportion that they will permit movements therethrough of the prong and shank of said hook and will prevent movements 30 therethrough of said projection.

2. In a removable mounting for a metallic

hook upon a flexible body, said hook having a curved prong and a shank provided with a projection, a fabric strip engaging the opposed sides and secured to said body, said strip being provided at one side of the flexible body with a flap and provided at the opposite side of said body with a pair of eyelets for a mounting therein of said hook, the apertures of said eyelets being of such proportion that they will prevent a movement therethrough of the projection of the shank, and will permit movements of the curved prong and shank therethrough. 40

3. In a removable mounting for a hook on 45 a flexible body, said hook having a prong, and a shank provided with a projection, a flexible strip engaging the opposed sides and secured to said body, said strip being provided at one of the sides of said body with a pair 50 of eyelets for a mounting therein of the hook, that part of the strip at the side of the flexible body opposite to the eyelets being provided with a flap, the proportion of parts being such that the prong and shank of the 55 hook may be moved through said eyelets, the projection operating as a detent to prevent a movement thereof through said eyelets.

In testimony whereof, we have affixed our signatures.

GLEN L. POPE.
ABE COHEN.
